UNITED STATES PATENT OFFICE.

SAMUEL W. OGLESBY, OF LONDON, ENGLAND, ASSIGNOR TO HUGH STEVENSON & SONS, LIMITED, OF MANCHESTER, ENGLAND, A LIMITED COMPANY OF THE KINGDOM OF GREAT BRITAIN.

CONTAINER.

1,345,021.

Specification of Letters Patent. Patented June 29, 1920.

Application filed January 5, 1920. Serial No. 349,441.

To all whom it may concern:

Be it known that I, SAMUEL WESLEY OGLESBY, a subject of the King of Great Britain, residing at London, England, have 5 invented certain new and useful Improvements in Containers, of which the following is a specification.

This invention relates to containers of paper, pasteboard and similar materials, 10 and resides in the application to such containers of a sheet metal reinforcing mouth suited to the reception and retention of removable disk closures.

A receptacle embodying the invention is 15 shown in the accompanying drawings, in which—

Figure 1 is a side view, partly in elevation and partly in section, showing the receptacle with the closure in place; and

20 Fig. 2 is a fragmentary view of an enlarged scale of a portion of Fig. 1.

The receptacle is shown at 3 and is constructed in any known manner of paper, paste board or equivalent fibrous plastic 25 material.

A continuous sheet metal reinforcing ring is permanently seamed to the mouth of the receptacle 3 by a rolled joint 4 and is formed with a rounded inwardly projecting bead

5, a groove or recess 6 below the bead, and 30 an inwardly projecting flange 7 defining the lower edge of groove 6 and serving as a seat for the disk closure 8. The closure 8 is larger than the opening into the receptacle between opposed portions of bead 5 35 and hence is snapped past the bead into contact with flange 7.

The receptacle above described may be water-proofed and used to contain liquids, particularly viscous liquids such as jams, 40 honey and the like or it may be used to contain various dry materials.

What I claim is:—

The combination of an open mouthed container of fibrous plastic material, and a continuous sheet metal reinforcing ring clamped to the margin of said mouth, said ring including a rounded bead embracing said margin and projecting inward with reference to the container, a flange also projecting inward below said bead, and a groove between said flange and bead adapted to receive and confine the edge of an insertible disk larger than the opening within said bead. 55

In testimony whereof I have signed my name to this specification.

SAMUEL W. OGLESBY.
